JACOB A. KISSELL AND NATHAN BLICKENSDUFER, OF CHICAGO, ILLINOIS.

Letters Patent No. 64,774, dated May 14, 1867.

IMPROVEMENT IN LIGHTNING CONDUCTORS.

The Schedule referred to in these Letters Patent and making part of the same.

TO ALL WHOM IT MAY CONCERN:

Be it known that we, J. A. KISSELL and N. BLICKENSDUFER, of Chicago, in the county of Cook, and State of Illinois, have invented certain new and useful improvements in Lightning Conductors; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists in constructing the flat conductor with ribs at the edges to give it greater strength, and prevent it from being torn or broken, and also to render it more rigid.

Figure 1 is a side view.

Figures 2, 3, and 4, end views of the same.

In using the flat copper rod as a lightning conductor, experience has demonstrated that when made of a thin strip of uniform thickness, in the usual manner, it is liable to be torn or broken at the edges, and when the edge has become once fractured, it is liable to become soon severed, thereby to destroy its use as a conductor. To remedy this difficulty the strip has been strengthened by "wiring" the edges, that is, by turning the edges of the strip over a piece of wire, as is usual with tinnings. This plan, however, necessitates a separate operation, adds to the expense, and it is found that the iron wire soon rusts and becomes destroyed. To obviate these difficulties and provide a rod having the requisite strength, without an unnecessary increase of the metal, we roll out a strip of the proper width and thickness to form the rod, and at the same time form on the edges a rib, *a*, of greater thickness than the body of the rod, as shown in the drawings. These ribs *a* are formed at the same operation which produces the strip itself, it being done by passing the strip between rolls provided with corresponding grooves, in the same manner that railroad rails and similar articles are rolled. If desired, a central rib, *b*, may be formed at the same time and in the same manner; but this central rib we do not consider of so much importance as those on the edges, as shown in fig. 4. The rod thus constructed is intended to consist of one continuous flat strip, and be put up in that condition, without being twisted or otherwise altered in form, except at the upper end, where that portion which projects above the building is to be made tubular, in order to give to it the necessary rigidity, to support itself and the point. The rod is to be attached to the building without the use of insulators, by simply nailing strips crosswise over the rod against the building. By this method of constructing the conductor, we are enabled to furnish a rod having its edges strengthened without wiring or subjecting it to any additional process or operation.

Having thus described our invention, what we claim, is—

A lightning conductor consisting of a strip of copper, having the ribs *a* formed solid therewith, as herein shown and described.
